UNITED STATES PATENT OFFICE.

HENRY FRALICK, OF GRAND RAPIDS, MICHIGAN.

DESIGN FOR A HORSESHOE.

49,726.

Specification for Design.

Patented Oct. 3, 1916.

Application filed January 29, 1915. Serial No. 5,156. Term of patent 14 years.

To all whom it may concern:

Be it known that I, HENRY FRALICK, a citizen of the United States, and a resident of the city of Grand Rapids, in the county of Kent and State of Michigan, have invented a certain new, original, and ornamental Design for Horseshoes, of which the following is a specification, which, taken in connection with the accompanying drawing, fully discloses the design that others may understand the same.

In the drawing: Figure 1 is a perspective view showing the design of a horse shoe; and Fig. 2 is a view taken from beneath the shoe.

The design comprises an attaching plate 1 curved as shown and formed substantially U-shape having spaced apart legs provided with openings as shown, and underneath the same a plate 2 also having spaced apart legs and of the formation shown best in Fig. 2 is positioned. Each of the plates 1 and 2 adjacent its forward end is provided with a rearwardly extending curved offset 3 which offsets lie one above the other, and each of the legs of plate 1 at its rear end is formed with a widened section 4 as shown, the similar legs of plate 2 being formed also with the widened section as indicated at 5 lying directly beneath the similar section of plate 1. A plurality of secur-

ing devices 6 pass through the lower plate 2 and are detachably secured to the upper plate in any suitable manner, it being noted that these securing devices are located at the projecting and widened portions of the plates at 3, 4 and 5. The front end of the lower plate and the rear ends of each of the legs thereof are turned down at substantially right angles as indicated at 7, it being noted that the front of plate 2 is much wider than the rear ends of the legs and that the turned down portion 7 at the front is accordingly much wider than the turned down portions 7 at the rear as fully shown in the drawings.

With the design as thus shown and described, a shoe of ornamental appearance is provided and one that conveys an impression of lightness combined with strength and rigidity.

I claim:

The ornamental design for a horse shoe substantially as shown and described.

In testimony whereof, I have hereunto affixed my signature in the presence of two witnesses.

HENRY FRALICK.
